C. D. McLEAN

ROSETTE FOR ELECTRIC WIRING

Original Filed Aug. 19, 1920

UNITED STATES PATENT OFFICE.

CHARLES D. MCLEAN, OF BERLIN, NEW HAMPSHIRE, ASSIGNOR, BY DIRECT AND MESNE ASSIGNMENTS, TO MECHANICAL & ELECTRICAL MANUFACTURING CO., INC., A CORPORATION OF MAINE.

ROSETTE FOR ELECTRIC WIRING.

Application filed August 19, 1920, Serial No. 404,497. Renewed April 11, 1924.

To all whom it may concern:

Be it known that I, CHARLES D. MCLEAN, a citizen of the United States, residing at Berlin, in the county of Coos and State of New Hampshire, have invented certain new and useful Improvements in Rosettes for Electric Wiring, of which the following is a specification.

The invention has for its object to provide a simple and inexpensive construction of wiring rosette adapted to be secured to a ceiling, wall or other fastening, there to form a juncture between the house wiring system and the wiring of a drop light or any other electrical apparatus adapted to be supplied therethrough.

The invention also provides a means whereby rosettes constructed in accordance therewith may be used in connection with any one of or any practical combination of the conventional types of wiring at present employed and when such universal use of the device is utilized the modification made necessary by the occasion is affected by the workman using the device and when made such modification does not in any way affect the outward appearance of the device to make the same unsightly.

The device is made in two parts that it may be disjoined, when necessary, and is constructed and joined in such a manner as to obviate all damage of fire and also the necessity of the using of a separate design of rosette for each system of wiring, thus materially reducing the cost of material and labor.

In its more detailed nature, the invention resides in those novel details of construction and arrangement of parts, all of which will be first fully described in the following specifications, pointed out in the appended claims and illustrated in the accompanying drawings, in which:

Figure 1 is a perspective view of the invention in use in a concealed wire system, the parts being shown separated.

Figure 2 is a plan view of a base member with two of the thinned rim portions knocked out to allow for the insertion of terminals of the wires of an open cleated wire system, the latter being indicated in dot and dash lines, the dotted lines illustrating the manner in which the terminals of a

metal moulding covered system may be inserted.

Figure 3 is an inverted plan view of the removable cover half of the device.

Figure 4 is a detail section taken substantially on the line 4—4 on Figure 2.

Figure 5 is a detail cross section of the base member and its removable cover half, the parts being separated.

Figure 6 is a detail perspective view of one of the retaining clips carried by the base.

Figure 7 is a similar view of one of the cover plate carried clip members.

Figure 8 is a detail view illustrating the manner in which the thinned rim flange portions are knocked out and filed down, when the same is necessary.

In the drawings in which like numerals of reference indicate like parts in all the figures, 1 represents a base member, in the nature of a cylindrical shell constructed of porcelain or other suitable material, including a central rib portion 3 projected from the base plate 2 and which is broadened at its outer ends to accommodate a countersunk bore 4 adapted to receive screws 5 for fastening the device to a wall, ceiling or similar fastening.

The cylindrical base shell 1 is formed by an annular flange 6 projected from each side of the base plate, the shorter or wall engaging portion of which is continuous, while the one projecting from the opposite side, is recessed at 7, the purpose of which will presently appear.

The flange 6 also includes a thin rim portion 8 projecting slightly beyond the plane of the said flange and the central rib 3 and adapted to provide a seat for the cover or cap member 10. The said cap member is in the nature of a hollow cap having a flange 11 adapted to seat within the rim portion 8 and to bear on the top of the interrupted broad flange 6. The cap is centrally bored, as at 12, to allow for the passage of the wires of a drop light or other apparatus as shown in Figure 1. The said wires after entering the cap are made fast to the binding screws 13 of a pair of contact members 14 herein-after again referred to.

For cooperatively connecting the base member 1 to the cap member 10 so that such

connection will present a positive and safe conduction of the electric current therethrough and also to form a firm but easily removable locking medium, I provide the 5 base 1, with a pair of contact members 15 which also have a supplemental spring clip member 16 fastened thereto and adapted to exercise a tight frictional engagement upon the head portion of the cooperating contact 10 member 14 carried by the cover cap when turned to its operative position therebetween.

The contact members 15—16 are placed one at each side of the central partition rib 15 3, thereby rendering impossible the short circuiting of the wires entering the base through the apertures 9 or otherwise as hereafter explained.

The wires entering the base, from what 20 ever system is in use, are fastened to the binding posts 17 of the contact members 15—16.

By reference to Figures 2 and 3 and also 25 6 and 7, it will be seen that by placing the cap member 10 in the proper position within the flange 8 of the base and turning as indicated by the arrows on the first mentioned of the figures, it will be understood that the head portion of the cap carried contacts 14—14 will come into position to be 30 tightly held between the spring members 15—16, 15—16.

In Figure 1, I have shown the device as 35 used in a concealed wire system but one of the main features of the invention resides in its applicability to any of the conventional types of wiring systems and in order to affect this result, I make the following provisions.

40 The dot and dash lines on Figure 2 illustrate the manner of induction of the wires of an open cleated wire system into the base member and the dotted lines illustrate the induction of those of a metal moulding covered system.

It is when these methods of wiring are to be accommodated that the cut out portions 7 come into use as will be now explained.

It will be seen by reference to Figures 1, 50 2 and 8 that the places at which the cut out portions 7 occur, leave a very thin wall portion 18 which normally remains as shown in Figure 1, but which may be "knocked out" in a manner illustrated in

Figure 8 and the rough edges filed smooth 55 to present a smooth appearance from without in order to accommodate one wire at each side as indicated by arrows on Figure 2.

From the foregoing taken in connection 60 with the accompanying claims, the novel features will be readily apparent to those familiar with such appliances.

What I claim is:

1. In a device of the character wherein is 65 provided a base member and a cap with interlocking contacts for retaining the cap on the base; a base member comprising a bottom plate, a thin annular rim or shell, a transverse partition and a thick annular 70 wall adjacent to the shell and having intervals for the passage of wires, said shell adapted to be broken out at said intervals, and said partition having holes for fastening devices, substantially as shown and de- 75 scribed.

2. In a device of the character wherein is provided a base member and a cap with interlocking contacts for retaining the cap on the base; a base member comprising a bottom plate, a thin annular rim or shell, a transverse partition and a thick annular 80 wall adjacent to the shell and having intervals for the passage of wires, said shell adapted to be broken out at said intervals, 85 said partition having holes for fastening devices, said shell projecting beyond said annular wall to embrace the cap.

3. In a device of the character wherein is 90 provided a base member and a cap with interlocking contacts on the cap and base; a base member having an annular thick flange with wire spaces at intervals and having a thin annular shell with portions overlying 95 said spaces adapted to be broken out.

4. In a device of the character wherein is provided a base member and a cap with interlocking contacts on the cap and base; a base member having an annular thick flange with wire spaces at intervals and having a thin annular shell with portions overlying 100 said spaces adapted to be broken out, said base portion including a transverse partition with holes for fastening devices, and said base member having holes through its 105 bottom for the passage of wires, substantially as shown and described.

CHARLES D. MCLEAN.
